UNITED STATES PATENT OFFICE.

JOSEPH N. PEPIN, OF CHICAGO, ILLINOIS.

PHONOGRAPH.

Original application filed September 2, 1922, Serial No. 586,003. Divided and this application filed May 11, 1923. Serial No. 638,192.

My invention relates to that general class of devices known as phonographs or talking machines, and is a divisional application of my application, Serial Number 586,003, filed September 2, 1922, and relates particularly to the improvement of the associated parts of phonographs.

The invention has among its objects the production of a device of the kind described, which is simple, efficient, convenient, neat and attractive in appearance, compact, durable and satisfactory for use wherever found applicable.

The invention has among its further objects the production of a machine of the kind described having means for adjustably counterbalancing the weight of the tone arm and to provide an improved type of mounting for the tone arm.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a side elevation, partly in section, of my improved device;

Fig. 2 is a section taken substantially on the line 2-2 of Fig. 1;

Fig. 3 is a section taken substantially on the line 3-3 of Fig. 1;

Fig. 4 is a section taken substantially on the line 4-4 of Fig. 5; and

Fig. 5 is a section taken substantially on the line 5-5 of Fig. 4.

Referring to the drawings, wherein the preferred embodiment of my invention is shown, the mechanism illustrated consists of a tubular tone arm casing or support 1 and a cooperating tubular tone arm part 2 slidably engageable therewith. A sound box or reproducer 3 is connected at the free end of the tone arm 2 and carries the stylus-receiving member 4 arranged to cooperate with the record 5. The top of the cabinet of the talking machine is indicated at 6. The tone arm casing or support 1 is tubular and is preferably mounted on the cabinet so as to be adjustable relatively thereto. The part 1 is preferably L-shaped, or is turned

or bent down, as indicated at 7 and has a spherical enlargement at its base. The portion 8 not only provides a bearing for the tone arm, as will be hereinafter described, but also acts as a reinforcement for the arm at this portion.

A sleeve or casing 9 is secured to the cabinet at the opening 10 to the sound chamber of the cabinet, said sleeve having an inwardly directed annular flange 11 at its upper end. A socket bearing or ring 12 having its lower outer edge cut away to form a horizontal flange 13 and a vertical annular flange 14, radially inwardly thereof, fits over and within the flange 11 of the sleeve 9 and is rotatable thereon to form a bearing therefor.

A cooperating lock member or ring 15 is arranged within the sleeve 9 and is secured to the part 12 by screws 16, or the like, to prevent accidental withdrawal of the part 12. A pair of pivot pins 16, carried by the bearing ring 12, extends through said ring and projects inwardly of its bearing surface to engage recesses in the ball 8 of the tone arm to permit said tone arm to pivot about the aligned axes of said pins. Thus it is seen that not only is there a rocking movement of the tone arm about the axes of the pins 16 permitted, but that the entire tone arm and the parts 13 and 15 carried thereby may be rotated relative to the sleeve 9 in a plane perpendicular to said rocking or pivotal plane, thus permitting a universal movement of the tone arm so that the free end of said arm has a limited vertical movement as well as a movement in a horizontal plane.

In order to reduce friction as much as possible so that the arm may be easily swung or turned in a horizontal plane, I preferably provide roller bearings 17 between the sleeve 9 and the ring 15. These bearings may be mounted by means of screws 17', or the like, on the flange 11 of the collar part 9 so that the roller will engage the opposed surfaces of the flange 13 and the part 15. Recesses or cut-away portions 18' may be provided at circumferentially spaced points about the inwardly extending flange 11 and into which said rollers may be positioned.

As shown more clearly in Figs. 2, 4 and 5, I prefer to yieldably support or counterbalance the weight of the tone arm and its associated parts so that its outer or free end is maintained substantially with the correct thrust upon the record but permit a slight

vertical play of the arm when the mechanism is in operation. The means for this purpose comprises a spring 18 secured at one end of the base of the tone arm, the other end being adjustably secured by means of a screw 19, or the like, to a bracket 20 carried by the ring 15; whereby the tension of the spring may be varied as desired. The spring not only supports the free end of the tone arm, but to a certain extent acts as a shock absorber when the tone arm is turned laterally into engagement with the record, thereby reducing the wear on the record and the stylus.

15 The tone arm part 2 is both rotatable and slidable longitudinally relative to the tone arm part 1, the limit of travel of the sliding movement being controlled in a manner to be described. In Fig. 1 it will be particularly noted that I have provided a slot in the tone arm part 2 and extending substantially spirally therealong, while the part 1 has threaded through the wall thereof a pin 22, the inner end of which is reduced and positioned within the slot for properly guiding the part 2 in its movement. Apertures 23 are provided in the part 2 adjacent each end of the slot 21 to form end stops, and into these apertures is adapted to be positioned a locking pin or plunger 24 securely retained within either one of the apertures by means of the spring member 22', one end of which is rigidly attached to the arm 1 and the other end supporting the pin 24. In this manner it is necessary that a slight pressure be exerted to turn the arm 2 in order to overcome the resistance of the detent 24 in the stop holes 23. Thus not only is the tone arm locked in place in the part 1, and its movement governed by the slot and plunger connection shown, but in its two extreme positions the same is yieldably locked in position.

45 Having thus described my invention, it is obvious that various immaterial modifications may be made in the same without departing from the spirit of my invention;

hence I do not wish to be understood as limiting myself to the exact form, construction, arrangement and combination of parts 50 herein shown and described or uses mentioned.

What I claim as new and desire to secure by Letters Patent is:

1. In a device of the kind described and in combination, a phonograph comprising a table, a tone arm having an enlarged ball portion at one end, a collar adapted to be mounted on said table at the sound chamber thereof and having an inwardly directed annular flange provided with circumferentially spaced recesses therein, an anti-friction roller mounted on said annular flange in each of said recesses, ring members arranged at the upper and lower sides of said flange and engageable with said rollers and with the ball portion of the tone arm to form a bearing therefor, and means for resiliently counter-balancing the weight of said tone arm.

2. In a device of the kind described and in combination, a phonograph comprising a table, a tone arm having an enlarged ball portion at one end, a collar adapted to be mounted on said table at the sound chamber 75 thereof and having an inwardly directed annular flange provided with circumferentially spaced recesses therein, anti-friction rollers mounted on said annular flange in said recesses, ring members arranged at the upper 80 and lower sides of said flange and engageable with said rollers and with the ball portion of the tone arm to form a bearing therefor, and means for resiliently counter-balancing the weight of said tone arm, said last-mentioned means comprising a spring 85 secured at one end to said ball portion of the tone arm and a screw carried by one of said ring members and adjustably secured to the other end of said spring.

In testimony whereof, I have hereunto signed my name.

JOSEPH N. PEPIN.
